UNITED STATES PATENT OFFICE.

FREDERICK SONN, OF WOODMERE, LONG ISLAND, NEW YORK.

PICTURE-CARD FRAME.

Application filed June 9, 1922. Serial No. 567,020.

To all whom it may concern:

Be it known that I, FREDERICK SONN, a citizen of the United States of America, residing at Burton Ave. and Crawford Road,

- 5 Woodmere, Long Island, in the county of Nassau and State of New York, have invented certain new and useful Improvements in Picture-Card Frames, of which the following is a specification.
- 10 This invention relates to pictures and card frames and has special reference to a picture or card frame formed from a single blank of card board like material cut and bent to shape.

15 One important object of the invention is to provide a novel form of picture frame made from a single blank of foldable material and constituting a new article of manufacture.

A second important object of the invention is to provide a frame of this description wherein a novel folding of the material from which the frame is made will provide slits or recesses for the reception of the edges of the card or picture to be framed thereby dispensing with the necessity of paste or other means of holding the picture in position.

With the above and other objects in view, the invention consists in general of certain 30 novel details of construction and combinations of parts hereinafter fully described, illustrated in the accompanying drawings, and specifically claimed.

In the accompanying drawings, like characters of reference indicate like parts in the several views, and:—

Figure 1 is a plan view of the blank from which one form of the frame is made.

Figure 2 is a view of said blank partly folded.

Figure 3 is a view showing the front of the completed frame.

Figure 4 is a section on the line 4—4 of Figure 3.

45 Figure 5 is a plan view of a blank for a modified frame.

Figure 6 is a view of the modified blank partly folded.

50 Figure 7 is a front view of the completed modified frame.

Figure 8 is a section on the line 8—8 of Figure 7.

In the form of the invention shown in Figures 1 to 4 inclusive there is provided a blank cut from a single sheet of cardboard or other foldable material. This blank has

a rectangular center portion 10 from which extend trapezoidal end flaps or portions 11 defined from the body of the blank by fold lines 12 and each divided into three strips 60 of substantially equal width by fold lines 13 extending parallel to the fold lines 12. Similarly, trapezoidal side flaps or portions 14 are defined from the body by fold lines 15 and are divided into three substantially 65 equal strips by fold lines 16, these strips being the same width as the end strips. The under side of each of the outermost strips is provided with a gummed field 17. 70

In folding the blank the three strips of each end and side portion are folded on the fold lines to form a triangular tube, the latter being then folded over on the body and these secured by moistening the gummed 75 field and pressing it down. This provides a frame having a flat back or central portion surrounded by triangular ribs.

In the form of the device shown in Figures 5 to 8 there is provided a blank having a 80 rectangular central portion or body 18 from which extend end flaps or portions 19 of rectangular form and defined from the body by fold lines 20. These end flaps or portions are divided into three strips by fold lines 85 21. Side flaps 22 are also provided which are defined from the body by fold lines 23. These side flaps are divided into three strips by fold lines 24 parallel to the fold lines 23. Of these three strips the innermost is of rectangular form, the middle strip of trapezoidal form with its longer side next the rectangular strip and the outermost of similar trapezoidal form with its shorter parallel side joining the middle strip. The side flaps are thus of general rectangular form, provided with opposed V-shaped notches 25 in the end edges adjacent the outer edges. The under side of each of the outermost strips of the side flaps is provided with a gummed 90 field or may be gummed in folding the blank to make the completed form. 95

In folding the blank for this style of frame the side flaps are bent on the fold lines to form triangular tubes which are 100 bent over onto the body and these secured after which the end flaps are similarly bent to form triangular tubes and the end angles 105 26 tucked into the ends of the side triangular tubes. This leaves the end flap loose from the body as shown in Figure 8 so that a card, picture or the like can be slipped into 110

position in the slot 27 at each end of the frame.

It will be seen that the articles thus formed can be used as advertising display frames, frames for mirrors, card pictures, as trays and various other ways. Also the blank may be made from celluloid, leather fabrics, or any other suitable material either plain or ornamented and either of a single thickness or of a thickness forming the base of the frame and covered with other material. For instance, heavy pasteboard may be used as a foundation and this may be covered with paper, thin leather, fabric or the like. Also the shape may be varied at will.

There has been thus provided a simple and efficient device of the kind described and for the purposes specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new is:—

1. A frame formed from a single sheet of foldable material having a central body

portion, and peripheral flaps each defined from the body portion by a fold line and each having a plurality of spaced fold lines parallel to the fold line defining the flap from the body, each of said flaps being bent on its fold lines to form a tube, said tube being folded over on the body, the ends of two opposite tubular members being provided with angularly cut portions, the ends of the remaining two tubular members being cut square and tucked into the ends of the tubular members having the angularly cut portions.

2. A frame formed from a single sheet of foldable material having a rectangular central body portion, end and side flaps defined from the body portion by fold lines and each divided into strips by fold lines parallel to the body defining fold lines, the side flaps being folded on their fold lines into tubular form and folded over on and permanently secured to the body, the end flaps being folded on their fold lines into tubular form, folded over on the body and having their ends tucked into the ends of the side tubular members, said end flaps being free from the body portion except at the folded line.

In testimony whereof I hereunto affix my signature.

FREDERICK SONN.
